UNITED STATES PATENT OFFICE.

WILLIAM L. PAUL, OF SOUTH BEND, INDIANA, ASSIGNOR TO OLIVER CHILLED PLOW WORKS, OF SOUTH BEND, INDIANA.

ENGINE GANG-PLOW.

1,148,043.

Specification of Letters Patent. Patented July 27, 1915.

Application filed March 9, 1912. Serial No. 682,665.

To all whom it may concern:

Be it known that I, WILLIAM L. PAUL, a resident of South Bend in the county of St. Joseph and State of Indiana, have invented 5 certain new and useful Improvements in Engine Gang-Plows; and I do hereby declare the following to be a full, clear, and exact description of the invention, such as will enable others skilled in the art to which it 10 appertains to make and use the same.

This invention relates to improvements in engine gang plows.

Heretofore, in the construction of engine gang plows, it has been proposed to pivotally connect the front ends of the plow beams to the truck frame, and to provide means for raising the rear ends of said beams and the soil-engaging parts carried thereby. With such construction, the pitch 20 of the plow unit while adjusting the same for depth of plowing, will be changed, unless a corresponding vertical adjustment of the front end of the beam is made.

One object of my invention is to so construct an engine gang plow, that the soil-engaging parts can be raised and lowered, or adjusted, by means connected only with the forward ends of the beams.

A further object is to so construct an engine gang plow, that the power necessary to raise the plow units shall be reduced to a minimum.

A further object is to provide an engine gang plow structure in which the plow units can be adjusted laterally with respect to each other, and that said plow units can swing or move both vertically and laterally during the operation of the plow.

A further object is to provide means, in an engine gang plow structure, which will insure uniform depth of plowing.

A further object is to so construct an engine gang plow that the width each plow unit will cut, can be regulated.

With these and other objects in view, the invention consists in certain novel features of construction and combinations of parts as hereinafter set forth and pointed out in the claims.

In the accompanying drawings; Figure 1 is a plan view showing one complete unit and a portion of the next adjacent unit of the plow structure. Fig. 2 is a side elevation of the structure embodying a plow unit,

and Figs. 3, 4, 5, 6 and 7 are views illustrating details of construction.

My improved plow structure comprises a plurality of units loosely connected together, as hereinafter described, to permit said units to flex vertically with relation to each other, in directions respectively, approximately parallel with and at right angles to the line of draft. Each unit of the structure comprises a truck frame unit or section, a plurality of plows and devices for connecting said plows with the truck frame unit or section, and for raising and lowering the plows. While the drawing shows only two units, still it is to be understood that any desired number may be employed and the construction of each being the same as all the others, a detail description of one of said units will suffice.

1 represents a truck frame unit, comprising two parallel angle beams 2 and 3, the rear beam 2 being disposed in a higher plane than the front angle beam 3, and said angle beams are spaced apart by a centrally located bracket 4.

An angle bar 5 is secured to the forward beam 3 near one end of the latter and projects therefrom in an outward direction at right angles to the line of draft, and to the bar 5 of the forward unit, the draft devices will be attached as hereinafter explained. A brace 6 is secured at one end to the outer portion of the angle bar 5 and at its other end to the forward angle bar 3.

Near respective ends of the front beam 3, brackets 7 having a general V-shape, are secured and to the rear vertical wall of each of these brackets, a U-bracket 8 is secured, the upper member of the latter being also bolted to the bottom face of the rear angle beam 2. It will be observed that the brackets 7 and 8 serve to assist in holding the beams spaced apart, and constitute, in effect, parts of the truck frame unit.

A vertical pin 9 is mounted at its ends in the upper and lower arms of each bracket 8 and with each of said pins, the yoke 10 of a trailing caster wheel 11, is connected by means of a clamp 12. A bracket 13, similar in construction to the brackets 8, is secured to the angle bar 5 in proximity to the free end of the latter, and the yoke 14 of a caster wheel 15 is swiveled in this bracket in the same manner as above described.

With each truck frame unit, several plow beams 16 are connected through the medium of pivoted, vertically movable bails 17. At the rear end of each plow beam, a soil engaging member 18 is located and provided with a wheel 19 which serves, in effect, as a revolving landside.

The forward ends of the arms of each bail 17 are provided with lateral projections 18^a 10 constituting trunnions,—one of which is mounted in a bracket 19^a secured to the forward angle beam 3 and the other of said trunnions is mounted in a bracket 20 depending from the rear angle beam 2,—the 15 bearings for the pivoted forward ends of the bail arms being thus disposed in the same horizontal plane and in alinement with each other.

In order to relieve the depending brackets 20 of excessive draft strain, their lower ends are connected, by means of rods 21 with the forward angle beam 3.

At the forward end of each plow beam, a coupling head 23 is located and provided 25 with a vertically curved web 24 having vertical elongated slots 25 and having serrations 26 on one face. Bolts 27 pass transversely through the forward portion of the plow beam and through the elongated slots 30 25 of the coupling head, and between the plow beam and the serrated face of the web 24^a, serrated block 27^a is located. The coupling head 23 constitutes a portion of the connections between the plow beam and bail, 35 and by means of the connection between the plow beam and said coupling head, as above described, the plow beam can be adjusted in a manner to level the soil-engaging parts.

The coupling head 23 is provided at the 40 forward end with two jaws 28—29 disposed one above and in alinement with the other. The upper jaw is provided with a threaded opening for the accommodation of a bearing block 30 having a conical bearing surface 45 for the upper conical end 31 of a shaft 32,—a conical bearing 33 being provided in the lower jaw 28 for the conical lower end 34 of said shaft. The intermediate portion of the shaft 32 is U-shaped in cross section and 50 its forward side is recessed to receive a sectional sleeve 35 mounted on the cross bar of bail 17. The shaft 32 is also made with a transverse groove 36 to receive a rib 37 on the sleeve 35. A clamp 37^a engages the forward side of the sleeve 35 and is engaged by the ends of a U-bolt 38 passing through the hollow shaft 32 and securing the latter to the sleeve.

It is apparent that the position of the 60 shaft 32 can be adjusted transversely on the sleeve 35 and thus permit adjustment of the distance of each plow beam from its neighbor.

A gage wheel 39 is provided for each plow beam and connected with the forward por-

tion of the same by means of a vertically adjustable standard 40.

The rear portion of each plow beam is curved downwardly as at 41 and the standard 42 of the soil-engaging parts is made 70 with a curved recess to receive the curved portion 41,—said standard and beam being adjustably secured together by means of bolts 43 passing through elongated slots 44.

A lifting lever 45 is provided for each 75 plow, and each of these levers is pivotally connected to the vertical web of the rear angle beam 2. Each lifting lever 45 is made L-shaped and its longer arm is provided with a suitable detent to engage a notched 80 segment 46 secured to the angle beam 2. The shorter arm 46 of each lever is connected, by means of a chain 47 with the adjacent bail 17. Springs 48 are provided to assist in lifting the plows, each spring 85 being secured at one end to the angle beam 2 and connected at the other end, through the medium of curved links 49 with the short arm of the adjacent lifting lever.

From the construction and arrangement 90 of parts above described, it will be seen that the forward end of each plow beam is connected with the truck frame through the medium of a vertically movable bail having horizontal pivotal connection at its forward 95 end with the truck frame and having connections at its rear end with the plow beam which will permit the plow beam to move vertically with the rear end of the bail and to also swing laterally. It will also be observed that the lifting lever is connected only with the forward end of the beam 100 through the medium of the bail and coupling devices.

To effect the raising of the soil engaging 105 parts of the plow, the operator will move the lifting lever to raise the rear end of the bail and the forward end of the plow beam. When the forward end of the plow beam is thus raised, the wheel 19 carried by the soil 110 engaging parts will rest upon the ground and the soil-engaging parts will rise with the beam and ride out of the soil.

When the plows are in their lowered or 115 working positions, as shown in Fig. 2, the pivotal connection of the rear end of each bail with the forward end of the corresponding plow beam, will be approximately in line with the pivotal connection of the forward end of the bail with the truck frame and the point of the greatest resistance or center of load on the soil engaging part. The point of greatest resistance or center of load on the soil-engaging part will, of course, vary in accordance with the condition of the soil and depth of plowing and it is therefore desirable that the plow shall be so adjusted that the point of greatest resistance or center of load on the soil engaging parts shall bear the proper relation to the 120 125 130

draft. Such adjustment can be readily effected by adjusting the curved rear end of the plow beam relatively to the curved seat on the plow standard, to raise or lower the forward end of the beam with which the bail, and consequently the draft, is connected.

By connecting the plow beams with the bails so that they can swing laterally, the 10 plows will be permitted to conform to the natural draft and also permit the plows to caster when turning a corner. When the plow structure is turned to the right the 15 swinging of the plows will cause them to approach each other, and in order to prevent conflict with the plows with each other when a short turn is made,—limiting means are provided and so constructed as not to interfere with the normal swinging of the 20 plows. Such limiting means may conveniently consist of telescoping rods 55—56,—one of said rods being attached to one plow and the other rod attached to the adjacent plow to the right. One of said rods will 25 preferably be made tubular for the reception of the other and the limit of movement of one plow toward the other effected by engagement of the solid rod with the bottom of the socket formed by the tubular rod.

30 It will be observed that the caster wheels at respective ends of the truck frame unit, are embraced by the end bails of the units but the height of the rear angle beam 2 is sufficient to permit the end bails to be raised 35 far enough to clear the caster wheels and said bails will not, therefore, interfere with the castering of the wheels when the plows are raised.

The bracket 7 at one end of the forward 40 angle beam 3 of each truck frame unit overlaps the adjacent end of the beam 3 of the next truck frame unit and lies parallel with the offset end 50 of the bracket 7 on the latter, the beams of adjacent truck frame units 45 lying in alignment with each other, as shown in Fig. 1. The overlapping portions of the brackets 7 on adjacent units are provided with aligned holes through which a bolt or hinge pin 51 passes loosely. The forwardly or outwardly projecting angle bars 5 of the various truck frame units are connected by rods 52, the ends of which are loosely connected with said angle bars.

The hinge connection at 50—51 will permit 55 the truck frame units to flex vertically at right angles to the longitudinal axes of said units, and the looseness of said hinge connection will permit the vertical flexing of the units relatively to each other at an angle 60 to the longitudinal axes of the truck frame units.

The draft chains 53—54 which connect 65 the plow structure with a traction engine, are connected with the angle bar 5 of the first truck frame units as shown in Fig. 1.

By shortening or lengthening one of these chains relatively to the other, the line of draft between the engine and the plow structure will be so changed, that the truck frames will be caused to swerve somewhat 70 and the plows to swing laterally, thus bringing the plows closer together or moving them farther apart (as the case may be) and thereby changing the width of furrow each plow will cut.

Having fully described my invention what I claim as new and desire to secure by Letters-Patent, is:—

1. In a gang plow, the combination with a traveling frame and a plow beam having 80 a plow body at its rear end, of a trailing bail pivotally connected at its forward end with the traveling frame and pivotally connected at its rear end with the forward end of the beam, a lever mounted on the traveling frame, and a connection between said lever and the bail, said lever and connection constituting the sole suspending and raising means for the plow beam and bail. 85

2. In a gang plow, the combination with a traveling frame and a plow beam having a plow body at its rear end, of a trailing bail pivotally connected at its forward end with the traveling frame and pivotally connected at its rear end with the forward end 90 of the beam, a lever mounted on the traveling frame, and a flexible connection between said lever and the bail, said lever and connection constituting the sole suspending and raising means for the plow beam and bail. 95

3. In a gang plow, the combination with a traveling frame, and a plow beam having a plow body at its rear end, of a trailing bail pivotally connected at its forward end with the traveling frame approximately in line 100 with the line of draft of the plow body and pivotally connected at its rear end with the forward end of the beam, a lever mounted on the traveling frame, and a connection between said lever and the bail, said lever and connection constituting the sole suspending and raising means for the plow beam and bail. 105

4. In a gang plow, the combination with a traveling frame and a plow beam having 110 a plow body at its rear end, of a trailing bail pivotally connected at its forward end with the traveling frame and pivotally connected at its rear end with the forward end of the beam, a ground wheel journaled in rear of the plow body and serving as a rolling fulcrum therefor, a lever mounted on the traveling frame, and a connection between said lever and the bail, said lever and connection constituting the sole suspending and raising means for the plow beam and bail. 115

5. In an engine gang plow, the combination with a truck frame, a draft member pivotally connected at its forward end to the 120 125 130

- truck-frame, a plow beam having its forward end pivotally connected to the rear end of the draft-member, means for vertically and laterally adjusting the forward end of the plow beam with relation to the rear end of the draft member, and means for simultaneously lifting the rear end of the draft member and forward end of the plow beam, substantially as set forth.
- 10 6. In an engine gang plow structure, the combination with a truck frame, and a vertically movable trailing bail pivotally connected therewith, of a plow, a coupling comprising means adjustable laterally on the cross bar of the bail, means connecting said coupling with the beam of the plow, said coupling also comprising parts movable at right angles to each other and permitting free vertical and lateral swinging movements of the plow.
7. In an engine gang plow structure, the combination with a truck frame, and a plurality of trailing bails pivotally connected therewith, of a plurality of laterally swinging plows connected with said bails, and two-part rods having relative longitudinal movement and connecting the plows to limit their lateral movement in one direction.
8. In an engine gang plow structure, the combination of a plow frame comprising parallel beams disposed in different horizontal planes and in different vertical

planes, means spacing said beams apart, brackets secured to said beams, trailing bails having pivotal mountings in said brackets and extending under the upper frame beam, rods connecting the brackets of the upper beam with the lower beam, plows having the forward ends of their beams connected with said bails and lifting means on the upper beam and connected with the bails under the same.

9. In an engine gang plow structure, the combination with a plow frame provided with trailing caster wheels at respective ends thereof, of vertically movable trailing bails pivotally connected with the plow frame forwardly of said caster wheels and embracing the latter, said plow frame having a part overhanging the bails, plows having their forward ends pivotally connected with the bails in rear of said caster wheels, lifting means on the overhanging part of the plow frame, and means connecting said lifting means with the bails to raise the forward ends of the plow beams.

In testimony whereof, I have signed this specification in the presence of two subscribing witnesses.
